Mrs. L. Jackson's,
Design for a Screen.
Patented Aug. 31, 1858.

1/2 1,045.

Pat 1045

James L. Jackson, of New York, N. Y.
Letters Patent No. 1045 - dated Aug. 31, 1858

The schedule referred to in these Letters Patent and making part of the same.

To all whom it may concern:

Be it known that I, James L. Jackson, of the City, County, and State of New York, have invented, discovered, or produced, a new and original design for a screen for a hot air register, or other purpose, and I do hereby declare the following to be a full clear and exact description of the configuration of the same reference being had to the accompanying drawing making a part of this specification, and which, represents in perspective a side and end of said screen.

To enable others to fully understand the nature of my design I will proceed to describe the same with reference to the drawings.

The front of the screen is in three panels viz: a central and larger one A, and two side panels B.B. which are smaller than the center one.

The central panel A. has for a center piece a bunch of fruit a. with leaves, enclosed in moldings b. and outside of the moldings are grapes, vines, and foliage, the whole being included, in a diamond shaped panel c. Outside of this panel c. is latticed open work d. extending to the beading which encloses one side of a marginal piece e. between the panels A and B. In this piece e. there is for a center, an escutcheon f. with volutes and foliage above and below it.

The panel B.B. and the end pieces C. (one only of the latter being seen in the drawing) are exactly alike, and have a vine leaf and volutes for a center (as seen at g.) flanked by open latticed work h.

The panels A.B.C. are surrounded by ornamental open work enclosed between delicate beadings i.i. The marginal moldings k. at the top and bottom of the plates or panels project upward and outward so as to leave the enclosed panels sunken. The whole is cast in open work, so as to leave as much open space in the plates as possible.

Having thus fully described my design what I claim as new, and of my discovery or production, is the ornamental configuration of the plates, designed for a screen, as above set forth and represented.

Witnesses.

David Pettigrew,
